Primary Examiner — Stacia A Cadmus(74) *Attorney, Agent, or Firm* — Gordon Rees Scully
Mansukhani, LLP(57) **CLAIM**

The ornamental design for a vehicle wheel, as shown and described.

DESCRIPTION

FIG. 1 is a perspective view of a vehicle wheel showing my new design;

FIG. 2 is a second perspective view thereof; and,

FIG. 3 is a front view thereof.

In the drawings, the broken lines depict environmental subject matter and form no part of the claimed design.

1 Claim, 3 Drawing Sheets**FIG. 1**

FIG. 2

FIG. 3
